DESIGN FOR A TEXTILE FABRIC OR SIMILAR ARTICLE

Robert E. Minger, Manhattan Beach, Calif., assignor to Hollywood Silk Mills, Los Angeles, Calif., a partnership composed of Mabs Ryden Barnes and Wallace E. Barnes

Application February 19, 1941, Serial No. 99,099

Term of patent 7 years

To all whom it may concern:

Be it known that I, Robert E. Minger, a citizen of the United States, residing at Manhattan Beach, county of Los Angeles, State of California, have invented a new, original, and ornamental Design for a Textile Fabric or Similar Article, of which the following is a specification, reference being had to the accompanying drawing, forming part thereof.

The figure is a plan view of a piece of textile fabric, showing my new design, a unit of which is contained between the dot-and-dash lines, the same being repeated in regular succession as indicated by the extensions upon the unit boundaries.

I claim:

The ornamental design for a textile fabric or similar article, substantially as shown and described.

ROBERT E. MINGER.
